LIQUID DEVELOPER TRAY AND FEED
ASSEMBLYJean-Paul R. Aubin, South Hadley, Mass., assignor to
General Aniline & Film Corporation, New York, N.Y.,
a corporation of DelawareFiled Dec. 19, 1963, Ser. No. 331,756
9 Claims. (Cl. 95—95)

This invention pertains to an improvement in liquid developer trays. It has particular application to liquid developer trays employed in the developing of moist diazotype materials. However, the invention has application also to developer trays and the like which are used for other purposes, and to liquid containers and dispensing devices in general.

In the document copying art, and particularly in the moist diazotype processes, it is highly desirable to have a uniformly fresh or freshly replenished solution at all times at all points in the apparatus. Various attempts have been made in the past to supply fresh solution to photographic developer trays, tanks, etc. Thus attempts have been made to replenish the solution, for example, by establishing a multiplicity of supply points so that fresh liquid can come from multiple sources. Efforts also have been made to assure uniform quality, homogeneity and freshness, etc., throughout the system by pumping the developer liquid continuously in a circulating manner. Such arrangements or procedures, while having certain merits, tend to result in unduly complex and expensive equipment which frequently is not justified. Moreover, they may tend to require larger inventories of liquid developer. While reference has been made above to developer, similar comments apply to fixing solutions, etc.

It is an object of the present invention to provide a liquid supply tray, i.e., a developer tray for photocopying purposes, which comprises a plurality of developer compartments and is equipped with a simple conduit means for supplying fluid simultaneously from a single point to the plural compartments in such a way as to maintain homogeneity of liquid, with suitable freshness and a minimum of spent solution consistent with the rate of liquid consumption throughout essentially all points in the system.

A further object is to provide a developer tray having a plurality of elongated parallel troughs, each of which is adapted to contain a replenishable supply of liquid, together with a simple means for assuring equal rates of replenishing all troughs at a similar rate.

A further object is to provide an apparatus comprising a simple tray structure which includes conduit means for directing and dividing the liquid flow so as to first use up the stalest part of the liquid.

A particular feature of the feed system includes the employment of a gravity feeder connected to a single point for maintaining the predetermined operating level at all points in the system and with substantially equal freshness of the liquid supplied to all points.

Additional and subsidiary features are found in the interconnection of the troughs at each end whereby, by flowing fresh liquids into one end of each trough, both ends of both troughs are constantly supplied with fresh liquid and the fresh quality of the liquid is maintained at all times.

Other objects and features will be apparent from the following description of the invention, pointed out in particularity in the appended claims and taken in connection with the accompanying drawings, in which:

FIG. 1 is an exploded perspective view of a simple form of the apparatus incorporating the present invention; and

2

FIG. 2 is a front elevational view of the assembled apparatus of FIG. 1.

As shown in FIG. 1, the tray structure comprises a rectangular container 21 divided by parallel troughs 23 and 25. In the arrangement shown, by way of example, there are just two such troughs, but the number may be increased to three or more if desired. The container 21 carries a pair of structural end plates 27 and 29. These are shaped and adapted to receive and maintain, in proper operating position, a plurality of rollers 31, 33, and 35, respectively. For this purpose the plates 27 and 29 are each provided with suitable slots 37, 37', 39 and 39', respectively. These slots are adapted to receive the shafts of the rollers 31, 33, and 35. Only one of these, the shaft 41, is shown at the left of the roller 31.

The intermediate roller 33, when assembled, normally rests upon the other two rollers and need not be actually journaled in the end plates. Any one of these rollers may be driven by suitable gear or other drive means, such as that indicated diagrammatically at 45. By applying power from a motor (not shown) to the drive 45, the roller 31 will be driven and, due to the frictional contact with the other rollers, all will be rotated. Thus, roller 33 may be driven by roller 31 and roller 35 in turn by roller 33. Positive drive may be applied to one or more additional rollers, besides 31, if desired.

Immediately outside the end plates 27 and 29, respectively, are lateral liquid compartments indicated at 51 and 53. These are best seen in FIG. 1. At the right end of the tray, an additional liquid receiving compartment 55 is shown which is adapted to receive the dispensing inlet element 57 of a suitable fluid supply unit. As shown, a barometric or gravity-type feeding device 59 is provided, which comprises a supply tank 61 and the usual means for entrapping air so that liquid will flow from the device 57 only when it has receded to a predetermined level in the compartment 55. The assembled arrangement of tray and feeder, plus the rollers is shown in FIG. 2.

The liquid compartments 51 and 55 at the right of FIG. 1 are each provided with an overflow outlet pipe. These are indicated at 63 and 65. These pipes project up into the compartments to a predetermined operating level where the liquid is to be maintained in the trough during development operations. In other words, the liquid will not ordinarily overflow through pipes 63 and 65 unless there is an accidental overfilling of the tray. The preferable arrangement is that the predetermined operating level be just barely below the overflow level, making allowance for the surface tension meniscus which forms at overflow.

Leading out from the liquid receiving compartment 55 is a feed conduit 71 which connects to a distribution tank 73 placed about midpoint of the front of the developer tray, and is so positioned that separate streams of liquid flowing from there to the two end compartments 51, 53 will require a substantially equal time and will encounter approximately an equal frictional resistance in flow. The distribution tank 73 located at the median point is connected by conduits 75 and 77 to the end compartments 51 and 53, respectively. The pipes 75 and 77 are essentially of equal length and equal diameter. With this arrangement, when liquid is supplied through conduit 71 to the median tank 73, assuming the apparatus is properly set at level, the flow rate of fresh liquid through the pipes 75 and 77, will be substantially equal.

By the means just described the lateral compartments 51 and 53 are constantly kept full of fresh incoming liquid, by gravity flow, up to the desired or predetermined operating level.

Each of the lateral compartments 51 or 53 is also connected by openings 81 and 83 with ends of the parallel troughs 23, 25. The preferred arrangement is one which

permits liquid from lateral compartment 51 to flow through the interconnection 81 into the left end of the rear trough 23, from which it may also flow indirectly through an interconnecting conduit 85 into the left end of the front tray. At the same time, liquid is supplied through pipe 77 to compartment 53 from which it flows through the interconnection 83 into the right end of the front tray 77. This tray is connected by a conduit 87 with the right end of the rear tray so that the liquid level in both ends of both trays is maintained equal. The flow is very simply controlled by gravity.

If desired, additional openings, as indicated in dotted lines at 81', 83', may be provided to connect each of the end compartments to both ends of both trays. However, for equalized flow, and to assure the active circulation or movement of liquid required to maintain a maximum of fresh developer solution at the point or points of use, it is preferred to keep the flow channel under close control at all times. This favors the method, as described, of bringing the fresh fluid directly into only one end of one trough and directly into the other end of the other trough, with cross-communication being established to supply the alternate ends indirectly. The length of the pipes 75, 77 preferably is properly adjusted to compensate for the time required for liquid to move laterally through compartments 51, 53, and through conduits 81, 85 and 83, 87, respectively. Such means are employed to equalize the flow throughout the system.

In operation of the device, it will be understood that the sensitized sheet material to be treated with the developer liquid is passed under or between the rollers, thereby receiving the developer liquid by surface contact. Thus the level of the solution will gradually decrease as the liquid is absorbed by the treated sheet material. As the level of liquid in the tray is lowered a small incremental distance by such depletion, the barometric feeder 57 allows a new supply of liquid to be introduced in a suitably small quantity, usually in small amounts at frequent intervals, into the end supply compartment 55. From this receiving compartment it flows through the conduit means 71, 75, 77, as described, and through the various other channels into the trays. With this arrangement, the circulation in both troughs 23 and 25 is from the ends toward the middle where the major consumption takes place. As the fluid is consumed, fresh fluid is constantly entering the system so that a substantially uniform freshness is maintained throughout the full length of both trays. There are no substantial areas of non-flow, such as corners or pockets, in which stale or spent fluid may accumulate.

It will be understood that the apparatus and the method of its operation are applicable to solutions other than developer fluid, such as fixing solutions and other treating liquids. The device may be employed to apply various coating materials wherever it is important to maintain a certain or known degree of freshness with constant or substantially constant replenishment of the material consumed. By means of this apparatus, properly set on a level base, the fresh liquid material is always introduced at both ends of all the troughs to flow, as shown, toward the center where it is taken up and out of the system. No special mixing means are required to prevent accumulation of stale areas of liquid. Obviously, if, for any reason, the liquid is consumed faster in any tray, or in any part of a tray, than in other trays or tray parts, the system will supply fresh liquid at the proper replenishment rate.

What is claimed is:

1. A developer tray which comprises, in combination, a plurality of elongated parallel troughs each adapted to contain a supply of developer liquid, a liquid conduit means of approximately equal flow resistance connected to each end of each trough and leading to a single supply

point, means for supplying liquid simultaneously to all said conduit means at said single point, and means for feeding liquid supplied to the ends of said troughs directly into an end of one trough and indirectly into the corresponding end of another trough while feeding directly into another end of the last mentioned trough and indirectly into the corresponding end of the first mentioned trough, whereby an essentially fresh liquid supply is continuously maintained in all parts of all troughs by feeding fresh liquid into each end of each trough as said liquid is consumed.

2. In apparatus of the character described, the combination which comprises a tray structure including a pair of spaced parallel troughs adapted to hold liquid up to an operating level, a separate supply compartment adjacent each end of said pair of troughs, conduit means for simultaneously supplying liquid by gravity to both said compartments, an interconnection between each of said compartments and each of said troughs, and liquid level maintaining means for supplying liquid to said conduit means so as to maintain a predetermined operating liquid level in both said troughs.

3. Combination according to claim 2 wherein the troughs are also interconnected for liquid flow between them.

4. Combination according to claim 2 wherein the troughs are interconnected at both ends for liquid flow between them.

5. Combination according to claim 2 wherein the troughs are interconnected at both ends for liquid flow, and wherein fresh liquid flows directly into a first one of said troughs and indirectly into the second trough at one end and flows directly into the second trough and indirectly into the first trough at the other end.

6. Combination according to claim 2 wherein a barometric feeder is provided to maintain by gravity feed the liquid level directly in said conduit means and indirectly in said troughs.

7. In apparatus of the character described, the combination which comprises a tray structure including a pair of parallel troughs each adapted to contain a liquid up to a predetermined operating level, end compartments adjacent each end of said trough and interconnected therewith for liquid flow from said compartments to said troughs by gravity, a liquid receiving compartment, a supply conduit system which includes a median feed point and which also includes a first supply conduit connected from said point to said liquid receiving compartment and a pair of substantially equal length branch lines, one running from said point to each of said end compartments, whereby fresh liquid is supplied from said median point to either end of either trough at essentially the same rate, thereby to substantially avoid differential exhaustion of the liquid in said troughs.

8. Combination according to claim 7 wherein a barometric gravity feeder is connected to said liquid receiving compartment to maintain a supply of liquid at said predetermined operating level.

9. Combination according to claim 7 wherein said troughs are interconnected at both ends by free flowing liquid conduits to prevent differences in liquid level.
